UNITED STATES PATENT OFFICE.

AMOS H. BOYD, OF MEDWAY, ASSIGNOR TO HIMSELF, JOHN ORVIS, OF WEST ROXBURY, JAMES J. COBB, OF BOSTON, MASSACHUSETTS, AND JOHN M. STERLING, OF CLEVELAND, OHIO.

IMPROVED MANUFACTURE OF BRAID.

Specification forming part of Letters Patent No. 37,541, dated January 27, 1863.

To all whom it may concern:

Be it known that I, AMOS H. BOYD, of Medway, in the county of Norfolk and State of Massachusetts, have invented a new and useful manufacture, which I call "Amosine Braid;" and I do hereby declare that the following is a full, clear, and exact description of the nature and mode of constructing the same, taken in connection with the accompanying drawings, which represent it in different forms.

My new manufacture, to which I have given the name of "Amosine Braid," is designed to be used either by itself or to be attached to other fabrics or tissues for the purpose of ornament, or for any other purpose to which it may be usefully applied. The mode of constructing this fabric which I have adopted with good success is by employing a sewing-machine having the usual mechanism for forming a seam with any of the ordinary forms of stitches, and having in connection therewith certain devices by means of which one or more threads, cords, braids, or other similar materials are interwoven with the threads of the sewing in a variety of ways, so as to form either a kind of gimp, or braid, or fringe by means of such interweaving, and also to sew the same onto the surface of cloth or other fabrics in any desired line or figure by the same operation. One, two, or more of these embroidering threads or cords may be used, of any desired size, color, or material, and interwoven with the sewing-threads in many forms, as will be readily understood from an inspection of the drawings, where several of the forms are represented which the fabric may be made to assume. All of these are made by the same general mode of operation, in which the sewing-threads may be considered as forming a warp and the ornamenting threads or cords a weft, which, by the operation of the machine, are interwoven with the sewing-threads at the same time that they are also interwoven with the cloth or other fabric by the operation of sewing. And although this braid assumes a considerable difference in ap-

pearance in the several figures, they all have this fundamental principle of construction and are made by the same machine.

In the drawings, Figure 1 represents one means of forming a braid or gimp, with one ornamenting thread or cord beside the sewing-threads crossing between each stitch of the sewing. Fig. 2 is a braid made with two cords drawn closely to the sewing-threads and both crossed at each stitch. Fig. 3 is a braid or gimp made with two threads with the loops of ornamenting-cord left more open, forming a kind of gimp. Fig. 4 is a fringe formed by extending the loops of the ornamenting-threads the required distance to one side. Fig. 5 represents net-work made of braids like Fig. 2, formed and sewed onto a piece of thin paper in any pattern desired, which braids, by the process of formation, are also sewed together at the intersections. After the net is completed the paper is removed, leaving the net complete. Fig. 6 is a gimp made with these cords beside the sewing interwoven in the order shown. Fig. 7 is a gimp made with two cords, with the intersections of the same with the sewing-threads made at every third stitch, as shown. Fig. 8 represents the varieties of interweaving; and Fig. 9 represents a section through the braid and cloth, to show the arrangement of the threads when two cords are used. The sewing-stitch represented is the "chain-stitch," so called; but any other sewing-stitch may be used in the same manner. From this section it may be seen that although the several forms shown have a different appearance the mode of operation by which they are made is substantially the same in all, and many other forms may also be made by varying the order of interweaving the ornamenting-cords, and also varying their color, material, and size.

The manner of arranging the mechanism which I have employed with success in connection with a sewing-machine for producing my new manufacture in its simplest forms is shown in Letters Patent granted to me April 2, 1861, No. 860; but other forms of mechan-

ism operating upon the same principle might be employed instead, and for making the more complicated kinds of braid other corresponding changes would be required in the devices which manipulate the ornamenting-cords corresponding to the style of the fabric to be produced.

What I claim as my invention is—
The new manufacture which I have called

"Amosine Braid," constructed substantially as described.

Boston, August 19th, 1862.

A. H. BOYD.
